MUSICAL INSTRUMENT

Josephus Thompson, Covington, and Morton S. Brockman, Cleveland, Ohio, assignors of one-sixth to said Thompson and five-sixths to Grossman Music Company

Application May 22, 1942, Serial No. 444,064

17 Claims.

(Cl. 84—388)

The inventions disclosed herein relate to trumpet type musical instruments and more particularly are improvements of the musical instrument disclosed in the co-pending United States patent application, Serial No. 398,775 which was filed June 19, 1941, by Josephus Thompson.

The prior patent application discloses a musical wind instrument in which the operating valves are in the lower portion of the body and wherein the operating or finger buttons connected thereto were on the top of the instrument. The valve stems connecting the buttons and valves therefor necessarily had to pass through long vertical channels in the body of the instrument and the friction thus encountered sometimes interfered with the proper playing of the instrument. Furthermore, the particular type of valve disclosed in the earlier instrument did not always provide a perfectly air-tight closure and leakage sometimes took place between the air passage and the compensator ducts. Also, because of the fact that the compensator ducts entered the primary channel at the bottom of the instrument, saliva under certain conditions had a tendency to interfere with the smooth operation of the valves. Cleaning of the instrument was also complicated for the same reason.

It is therefore the primary object of this invention to provide molded plastic wind instruments with body members having interconnected compensator ducts and primary air passages and wherein the said connections are made at places other than at the normal bottom portion of the body members.

Another object of this invention is to provide devices of the type mentioned which have improved types of valve devices and which devices are more precise and smoother in operation than those of the earlier instruments, which are more responsive to the touch of the player and which are easier to install, repair or replace.

These and other objects, features and advantages of these improved instruments will become apparent through a reading of the attached specifications and claims, taken in connection with the accompanying drawings in which like parts are designated by like reference characters and in which:

Figure 1 is a top or plan view of the simplest or preferred form of the instrument;

Figure 2 is a vertical sectional view of the same instrument taken along the line and in the direction of the arrows 2—2 of the Figure 1;

Figure 3 is an enlarged elevation of a por-

tion of the instrument, with portions thereof broken away to show interior construction and assembly;

Figure 4 is a vertical sectional view along the line and in the direction of the arrows 4—4 of Figure 3;

Figure 5 is a vertical sectional view taken along the line and in the direction of the arrows 5—5 of Figure 3;

Figure 6 is a vertical cross sectional view of instrument taken along the line and in the direction of arrows 6—6 of the Figure 3 and showing a valve open as when the button is depressed;

Figure 7 is a vertical sectional view of the instrument taken along the line and in the direction of the arrows 7—7 of the Figure 3;

Figure 8 is a plan view of one of the two forms of valves which may be used in the preferred form of the instrument;

Figure 9 is a side view of the same valve shown in the Figure 8 and also showing in broken lines an alternate view or open position thereof;

Figure 10 is an end view of the same valve taken along the line and in the direction of the arrows 10—10 of the Figure 9;

Figure 11 is an end view of the bottom portion of a valve stem used to operate the valve shown in the Figures 8, 9 and 10;

Figure 12 is a side view of the valve shown in the Figure 11;

Figure 13 is a bottom view of the valve stem shown in the Figures 11 and 12;

Figure 15 is a lateral and vertical sectional view of a slightly modified form of valve mechanism capable of use with this preferred type of instrument and also showing the said valve in the closed position;

Figure 15 is a longitudinal vertical sectional view of the modified form of valve mechanism shown in the Figure 14 and taken along the line and in the direction of the arrows 14—14 thereof;

Figure 16 is a lateral vertical sectional view of the same style of valve mechanism in the depressed or open position taken along the line and in the direction of the arrows 16—16 of the Figure 17;

Figure 17 is a longitudinal vertical sectional view of the same valve taken along the line and in the direction of the arrows 17—17 of the Figure 16;

Figure 18 is a top view of the right side only of a modified form of the instrument;

Figure 19 is a longitudinal elevation of the

portion of the instrument shown in the Figure 18, the view taken along the line and in the direction of the arrows 19—19 thereof;

Figure 20 is an elevation of a right hand outside portion of the instrument taken along the line and in the direction of the arrows 20—20 of the Figure 18;

Figure 21 is an end view of one of the compensator duct channelled members shown in the Figure 20;

Figure 22 is a vertical sectional view of the same channelled members taken along the line and in the direction of the arrows 22—22 of the Figure 21;

Figure 23 is a similar view of the small channelled member used in the instrument, the view taken along the line and in the direction of the arrows 23—23 of the Figure 24;

Figure 24 is an end view of the channelled member shown in Figure 23;

Figure 25 is a similar view of a third channelled member used in the instrument;

Figure 26 is a top view of the left half of the instrument;

Figure 27 is a longitudinal vertical elevation of the portion shown in the Figure 26 and taken along the line and in the direction of the arrows 27—27 thereof;

Figure 28 is a front end view of the left hand portion of the instrument, the view taken along the line and in the direction of the arrows 28—28 of the Figure 27;

Figure 29 is a vertical and lateral sectional view of the assembled instrument taken along the line and in the direction of the arrows 29—29 of the Figure 35;

Figure 30 is an exploded view of the parts shown in Figure 29 and more particularly showing sections of the Figures 18, 23 and 27;

Figure 31 is a lateral sectional view of the instrument taken along the line and in the direction of the arrows 31—31 of the Figure 35;

Figure 32 is an exploded view of the main portions of the body shown in the Figure 31;

Figure 33 is a portion of the view shown in the Figure 29 but showing the valve mechanism opened or in the depressed position;

Figure 34 is a plan view of the assembled portions of the instrument;

Figure 35 is a right side view of the assembled instrument;

Figure 36 is an exploded side view of the valve body and stem; and

Figure 37 is a lateral sectional view of the valve body and stem shown in the Figure 36.

Preferred form

The first two pages of the drawings show a simplified or preferred form of the trumpet. This particular model 49 is made of two similar or symmetrically molded halves which fit and are cemented together in the middle as shown. The three air valves 60 used to change the tone of the instrument are mounted in about the center or approximately midway between the front and rear end portions 43 and 44 respectively and on the top 41 of the instrument. The valve members 60 are each alike and are interchangeable and easily installed, replaced or repaired. The instrument may be made of molded plastic or composition material and is so designed that the two symmetrical sides of the circuitous air passage 49, the ducts 53, 54 and 55, the mouthpiece and bell portions 47 and 46 are formed with

in the unitary body of the instrument without the necessity of having to attach extraneous parts thereto.

The Figure 2 shows a vertical longitudinal section of the simpler and therefore, the preferred form of instrument and particularly shows the body member 49 as having a top portion 41, a bottom portion 42, a front end portion 43, a rear end portion 44 and a middle or central portion 45 therebetween. The aforesaid portions are named from the positions they occupy or the locations they are in while being played in the regular manner. The circuitous air passage 49 opens into or terminates at the mouthpiece portion 47 and passes downward across or through the rear end portion 44 to the bottom portion 42. At about the middle of the instrument and more particularly to the portion thereof designated as the middle section 45, the air passage 49 turns and goes backward to the rear end portion 44, then upward to the top portion 41. From there, it passes in a relatively straight line to the front end portion 43, then downward through the front end portion 43 to the front part of the bottom portion 42. It then passes rearward to the middle section 45 and then forward again through the lower part of the bottom section 42 to the front end section 43 where it passes upward toward the top thereof and terminates in a bell 46. The portion of the air passage which is designated by the character 52, tapers and enlarges gradually before terminating in the bell 46.

The portion of the air passage which is designated by the character 51 and which extends longitudinally through or across the top portion 41 between the front and rear end portions 43 and 44 is rectangular in cross-section and has flat and smooth top, bottom and side walls. The rest of the passage 49 may be made round in cross section as in a conventional metal instrument. The horizontal portion of the air passage which enters into the mouthpiece portion 47 may be enlarged as shown to receive the special mouthpiece 47a if desired. The portion of the air passage 49 which passes forward across the bottom portion 42, has a small opening 59 therein, at about the point where the passage turns upward and rearward. This small opening 59 is covered by the valve 58 which may be of a conventional design and is used to remove any moisture accumulating in the instrument. The two lateral holes 48 and 48a which extend from the middle portion 45 to the front and rear portions 43 and 44 respectively are below the top portion 41 are made to accommodate the fingers of the player so that the instrument may be played exactly like a standard cornet or trumpet.

The auxiliary air passages also known and referred to as compensator air ducts are of three different lengths, so that the instrument may be varied in tone according to the duct or combination of ducts engaged during play. The intermediate duct 53 which is located toward the rear of the instrument has an air passage which is medium in length. It passes downward in a somewhat looped formation through the middle section 45 and rearward under the opening 48 as shown. The long duct 55 similarly passes downward and then forward toward the front portion of the instrument and partly below the opening 48a. The middle duct 54 which is the shortest of the three in length, simply passes downward and upward through the middle section 45, as illustrated. Each of the three ducts 53, 54 and 55

extend or lie longitudinally in the body of the instrument and open into the floor of the rectangular section 51 of the main air passage. The three ducts may be entirely round in cross section or they may be formed with tapered rectangular terminal portions contiguous to the section 51 as indicated by the character 56 of the Figures 1, 2 and 3.

The top portion 41 of the instrument is provided with three internally threaded holes 53 which are above the termini of the three compensator ducts. These openings are made to receive the valve members 60 which are illustrated in detail on sheet two of the drawings.

The Figures 1 and 2 show a complete valve inserted in the rear opening of the instrument and directly over the terminal of the medium sized duct 53. The same figures show a valve body only, inserted over the short duct 54. The front opening 50 which is over the compensator duct 55 is shown entirely open and without any valve parts.

The Figure 3 is an enlarged view of the top part of middle portion 45 of the instrument and shows the construction and assembly of one form of air valve suitable for use with this particular instrument. Specifically the form of valve shown in the Figures 1 to 13 consists of a somewhat hollow body 60 which has an outside knurled surface for convenience in handling. It has a hexagon portion 61 which is convenient to use with a tool in case the valve body gets stuck in the instrument and is difficult to remove for replacement or repair. The bottom portion of the valve is that portion which is indicated by the character 62 and is threaded externally to fit the threaded portion 50 of the body member. The valve body 60 has sufficient space therein for the valve spring 64 and the small valve stem pin 65, and has an externally threaded ring 63 inserted therein which retains the valve spring 64 in place and which helps guide the slidable stem 66.

The valve stem 66 passes vertically through hexagon top portion 61, the valve body, the coiled spring 64 and ring 63 as shown. This valve stem 66 has a suitable finger button 67 mounted on the top thereof and also has the small horizontal pin therethrough which engages the spring 64 as shown.

The lower portion of the valve stem 66 is shown in greater detail in the Figures 11, 12 and 13. The lower end of the stem 66 has a substantially forked bottom portion 68 as shown. Each of the two pointed portions 69 are referred to herein as blade portions. They depend from the portion 68 and are tapered in opposite directions and form cam-like members which engage and operate the levers 73 hereinafter described in detail. The lower portion 68 of the valve stem, the two tapered blade portions 69 and a small portion of the stem 66 passes through the air passage 51 and they therefore, should be made as small as possible so that as little disturbance as possible is created in the air column passing therethrough.

If so desired, the three valves 60 may be mounted in the instrument body 40 slightly to the side thereof so that the portions of the valve stem 66 and 69 which project across the air passage 51 will be closer to one side wall thereof.

The top portion 41 of the body, at a point midway between the termini of each of the three ducts 53, 54 and 55 and at a point immediately below the valve stem 66, has a small rectangular recess 57 which receives the pointed

blades 69 and the two levers 73 operated thereby.

The effective portion of the valve member, namely, the valve leaves or plates 71 are simply two small metal sheets hingedly attached together around a pin 72 much in the manner of an ordinary door hinge. Each of the plates 71 has an open portion or slot 76 therein perpendicular to the pin 72 which receives the lever 73 of the opposite and co-acting portion 71. The levers 73 and the slots 76 should be made to fit as neatly as possible so that air leakage will be at a minimum. This particular assembly and construction is clearly shown in the Figures 8, 9 and 10. The pin 72 laterally passes through the body of the instrument at a point even with the top of the rectangular recess 57 and with the bottom of the straight air passage 51. This permits the valve plates 71 to lay flat in the two shallow recesses 75 which are formed along the bottom of the passage 51. The plates 71 are also of sufficient size to completely and securely close the two ends or termini of each of the ducts 53, 54 and 55.

When a duct is not engaged or opened for play the valve plates 71 are flat and smooth and remain in the position shown in the Figures 4 and 5. In this position the main air channel 51 is substantially clear. The slight obstruction caused by the valve stem members 68 are not sufficient to interfere with tone quality as all undesirable air currents or eddies are smoothed out in the passages 49 and 52 before reaching the bell 46. When the valve stem 66 is depressed and assumes the position shown in the Figure 6, the lower portion 68 of the stem and the levers 73 are also depressed into the rectangular recess 57 and at the same time the plates 71 rise in the rectangular passage 51, close the passage at that point and deflect the current of air through its particular duct and then back into the part of the main air passage which is on the other side of the valve stem.

Inasmuch as there is no direct connection between the plates 71 and the valve spring 64, a small auxiliary spring 74 is mounted on the lateral pin 72 in a manner causing the two plates, 71 to operate simultaneously and more effectively. It will be observed that each of the forked cam-like members 69 engage oppositely extending levers 73. So that the plates 71 are opened in unison.

There are obviously many types of valves which may be applied to this particular design of the instrument. For the sake of clarity however, a second form of valve is illustrated in the Figures 14, 15, 16 and 17. This second form of valve has a body portion 60 like that of the valve previously described. It too, has a valve spring 64 and a threaded portion 62 which fits the threaded openings 50 in the instrument body 40. The threaded ring 83, however is different from the previously described threaded disc 63 in that it has a lateral slot 84 which receives the top part of the lower portion of the valve stem member.

The valve stem member 86 differs from the previously described valve stem 66 in that it has a rectangular frame 88 on the bottom end thereof. This rectangular frame 88 is made to slide laterally through two grooves 89 in the side walls of the air passage 51, and also fits in the groove 94 thereabove. The central portion of the frame 88 is provided with a suitable opening large enough to pass the necessary volume of air needed to play the instrument. The portion of the body 40 directly below the valve frame 88

has a small Y shaped recess 81 which receives the horizontal bottom part of the frame 88 and the inside abutting edges of the valve plates 91.

Two valve plates 91 are hinged together in a manner similar to the previously described plates 7 except that they do not have the lever portions 13 thereon or the slots 76 therein. The valve plates 91 are made to fit over and securely cover the ducts 53 thereunder. A small auxiliary spring 94 similar to the spring 74 is mounted on the hinge pin to keep the valve plates 91 in the normally closed position. The hinge pin, which connects the two plates 91, does not extend through the body of the instrument as does the pin 72. This pin instead is short and enables the valve plate 91 to be simply laid in position through the opening 50, without other fastening means when the instrument is being assembled.

When the valve button 87 is depressed the lower horizontal bar or part of the rectangular frame 88 causes the two contiguous edges of the plates 91 to drop into the Y shaped recess 81. The two plates then pivot on the two lateral and parallel straight edges 82. The larger portions of the two plates are caused to rise and thus deflect the air current down and through its particular duct. The figures 14 and 15 show the modified form of the valve in the normal position, that is, when the adjacent compensator duct is closed and the main air passage 51 clear. The Figures 16 and 17 show the same valve in the depressed position and with the particular compensator duct open and interconnected with the main air passage 51.

It will be observed that, because of the small parts of the plates that drop into the openings 57 or 81 and the relatively larger parts thereof that rise to close the passage 51, an improved leverage effect is obtained and which effect makes the instrument more responsive to the player's touch. The plates 71 and 91 are therefore faster in operation and are played by strokes which are shorter and more effective.

Modified form

The modified form of the instrument which is shown on Sheets 3, 4 and 5 of the drawings differs from the previously described form, principally for the reason that the three compensator ducts 153, 154 and 155 engage or connect with the main air passage 149 at a point where the column of air is moving toward the rear of the instrument. Also the three air valves 160 operate on the side of the main air channel instead of on the top thereof as shown in the preferred form of the invention or at bottom thereof as shown in the co-pending patent application Serial No. 398,775.

The right hand or main portion of the body is molded out of a plastic material similar to the body portions 40 heretofore referred to. This portion of the body is broadly designated by the character 140 and is clearly shown in the Figures 18, 19, 30 and 32. It has a top portion 141, a bottom portion 142, a front portion 143, a rear portion 144 and a middle section 145, corresponding to the portions 41, 42, 43, 44 and 45 heretofore referred to. The upper rear part of the instrument has a mouth piece 147 and the upper front portion has a bell 146 70 in the conventional manner. The main air channel or passage 149 starts at the mouthpiece portion 147 and passes downward across or through the rear end portion 144 to the bottom thereof. Thence, it passes forward through the bottom 75

portion 142 to the front end portion 143, thence upward to the top portion 141 and thence rearward to a point in the top portion 141 slightly forward of the mouthpiece 147. From this point 5 it passes upward in the top portion 141 and thence forward again to the bell portion 143. The portion of the air channel indicated by the character 152 is tapered and flared as shown in the Figure 19 before terminating in the horn bell. The air passage 152 also lies slightly above and to the left side of the rectangular portion of the air passage 151 below it. The main air passage 149 heretofore referred to may have a cross section of any shape which permits 15 the free and uninterrupted flow of air. However, the portion of the passage designated by the character 151, which passes through the top portion 141 and through the middle section 145 of the instrument should have a rectangular cross section to accommodate the special valves 160 hereinafter described in detail. The drawings show an instrument having a round cross sectioned air passage before the horn bell, a piano-convex cross-section through the bottom portion 142 and the aforementioned rectangularly cross-sectioned portion 151 between the two. The top portion of the instrument 141, that is the portion immediately above the rectangular air passage 151 is divided longitudinally symmetrical. That is, the body member 140 contains one half of the air passage 152 and the other part of the body 180 hereinafter described in detail contains the other half of the air passage designated by the character 192.

35 The lower part of the instrument is not divided so evenly. Instead it contains practically all of the air passages 149 and 151.

Like the preferred form of the instrument the mouthpiece portion 147 may be equipped with a special metal mouthpiece and similarly the main air passage 149 is provided with a small valve and opening 159 at the front end of the lower portion 142, which is used to remove any moisture in the instrument.

45 The top portion 141 of the instrument and particularly the part immediately above the air passage 151 contains or has three internally threaded hollow portions 150 which receive the previously mentioned specially designed valves 160. The bottom portion of the instrument 142, that is the portion immediately below the air passage portion 151 is provided with two lateral openings 148 and 148a to decrease the weight of the instrument and also to accommodate the player's fingers, so that it may be played in the same manner that prior art tubular metal instruments are played.

55 The sidewall of the instrument above the main air passage 141 and at the hollowed portions 150 made to receive the valves 160, have side openings 157 therein which coincide with certain similar openings 164 in the valve body 160 and with certain openings 156a, 157a and 158a in channelled members 22, 23 and 25 hereinafter 60 described in detail. All of these matched openings are the same size as the air passage 151 and compensator ducts 153, 154 and 155 and permits the column of air to flow freely therethrough without any obstruction when a valve 160 is depressed.

65 The compensator air ducts 153, 154 and 155 which are used to change the tone of the instrument are molded or formed in three channelled members which are illustrated in the Figures 21, 22, 23, 24 and 25 inclusive. These mem-

bers containing the ducts are mounted on the right hand side of the instrument as shown in the Figures 20, 29 and 31. The long channelled member 22 which contains the duct 155 is mounted longitudinally on the side of the instrument and is so positioned that its terminal 156a coincides with the openings 156 in the aforementioned sidewalls and the opening 164 in the valve members.

The intermediate channel member 23 which contains the short duct 154 is mounted on the side of the instrument and is so mounted that the ends or termini 157a thereof coincide with the opening 157 in the side wall of the body member 140. Similarly the channelled member 25 containing the duct 153 is mounted with its terminal 158a coinciding with the openings 158 of the body member. The channelled members 22, 23 and 25 are mounted longitudinally in line and are located substantially on the top portion 141 of the instrument.

The left hand side of the instrument is not symmetrical or even in shape with the right hand portion as is the case in the preferred form of instrument heretofore described. The left hand portion 180 of the instrument is clearly illustrated in the Figures 26, 27 and 28. The Figures 29, 30, 31, 32, 33 and 34 show it attached to or associated with the right hand side 140. The right and left sides of the instrument as well as the channelled members 22, 23 and 25 are cemented together to make a one piece instrument body. The left body portion 180 also has a top portion 181, a bottom portion 182, a front end portion 183, a rear end portion 184 and a middle section 185 which coincide with the portions 141, 142, 143, 144 and 145 previously referred to. It also has two finger openings 188 and 188a which coincide with the openings 148 and 148a. The lower part of the member 180 namely the part through which the finger openings 188 and 188a pass is substantially flat and closes or forms the side wall of the air passages 149 and 151. The top portion 181 is projected outwardly to the side of the lower portion as shown in the Figures 26, 27, 28, 30 and 32 and contains the second half of the air passage indicated by the characters 187, 189 and one half of the flared bell portion 192.

The special valves used with this style of instrument are shown in detail in the Figures 29, 33, 36 and 37. Each member has a rectangular body portion 160. The body portion is box-like and has an open bottom and four side walls between which the valve stem and parts move. The top of the body is provided with a round tubular collar-like portion 161 just below which, there is a somewhat constricted throatlike portion 162 through which the valve stem 166 slides. The body portion 160 has two openings 164 in one side wall thereof which openings coincide with the aforesubscribed openings 156, 157 and 158 of the body members 140. The two end walls, that is, the forward and rearward laterally extending walls of each body member 160 have openings 163, at the lower edges thereof which openings coincide with the air passage 151 so that the column of air can pass freely.

The valve stem 166 is threaded at its top end to receive the finger button 167. The bottom portion is flattened and formed into a laterally extending plate 168 which is positioned in the instrument body so that it may move up and down during play between the two ends or terminals 156a, 157a and 158a of each of the ducts

155, 154 and 153 respectively. The extreme bottom of the valve stem 166 has a horizontal or flat plate 169 which moves up and down during play in the main air passage 151. The collar portion 161 of the valve member contains a small coiled spring 165 which fits between the throat 162 and the button 167. This spring tends to raise the valve stem 166 and its lateral and horizontal elements 168 and 169 respectively.

10 Normally the plate 169 is at the top or ceiling of the air passage 151 and permits the air currents in the passage to pass through without any obstruction, deviation or deflection whatsoever. When the valve 166 is depressed the horizontal plate 169 lies on the floor of the air passage 151 and the air currents thereat are deflected by the laterally extending plate 168 through the first of the particular duct openings. For example, in the case of the middle valve, the air is caused to pass successively through the openings 164, 151, 157a then through the short duct 154 and back to the main passage 151 through the openings 157a, 157 and 164 which are on the other side of the plate 168. The inside sidewalls of the valve bodies 160 may be provided with two aligned vertical grooves to accommodate the vertical side edges of the plate 168 so that the valve will operate smoother and also to make better air closures at those points.

15 It will be observed that the valve mechanism are interchangeable and may be very easily repaired or replaced. The valve bodies and stems are inserted in the openings 150 in the top of the instrument and are held in place by threaded collars or rings 171 which fit around the collar portions 161. The top portion of the rings are hexagon shaped to facilitate the use of a simple wrench when needed.

20 The modified form of the instrument also differs from the preferred form, in that the operation of the valve more nearly resembles the operation of the valves in prior art instruments. The movement of the valve actually coincides with the movement of the player's fingers. No leverage takes place in the valve and the valve is not caused to move faster than the player's fingers. The extent of finger motion is exactly the same as the stroke of the valve stem. For this reason by simply depressing the valve half 25 or part way it is possible to obtain musical effects which are not obtainable on the previously described preferred form of instrument, as this causes air to pass both through the main air passage 151 and through a compensator duct at the same time.

30 While these inventions have been described and illustrated in their preferred forms and while certain specific words and phrases have been used herein, it is to be understood that the disclosure is not to be considered in a restricted sense, as there may be many other forms or modifications of the invention which might also be considered to be within the scope of the following claims.

We claim:

35 1. A musical instrument, comprising, in combination, a body member including top, bottom, front and rear end portions and having a circuitous air passage therein, the air passage terminating into a mouthpiece at the said rear end portion and into a bell at the said front end portion, the said passage having a substantially straight part thereof extending longitudinally through the said top portion, the body member also having a set of compensator ducts therein 40 opening into the aforesaid straight part, and a

set of air valve members mounted on the body member top portion and projecting through the said straight part in a manner permitting the opening or the closing of the said ducts thereat.

2. A musical instrument of the type defined in claim 1 and further characterized by the said air passage straight part and the said set of valve members being in the same vertical plane.

3. A musical instrument, comprising in combination, a body member including top, bottom, front and rear end portions and having a circuitous air passage therein, the air passage terminating into a mouthpiece at the said rear end portion and into a bell at the said front end portion, the said circuitous air passage running through the said top and bottom portions and having a flat walled straight part extending longitudinally through the said top portion, the body member also having a set of compensator ducts therein opening into the aforesaid straight part and a set of air valve members mounted on the body member top portion and projecting through the said straight part in a manner permitting the opening or the closing of the said ducts thereat.

4. A musical instrument of the type defined in claim 3 and further characterized by the said air passage, compensator ducts and air valve members being in the same vertical plane.

5. A musical instrument, comprising in combination a body member including top, bottom, front and rear end portions and having a circuitous air passage therein, a mouthpiece member integral with the body member and opening into the rear end portions, a bell member integral with the body member and opening into the front end portion, the said circuitous passage running through the said portions and connecting the mouthpiece and bell members, the said air passage having a straight part extending longitudinally through the said top portion and having a wall thereat, the body member also having a set of compensator ducts therein opening into the aforesaid wall, and a set of air valve members mounted on the body member top portion and projecting through the said straight part in a manner permitting the opening or the closing of the said ducts thereat.

6. A musical instrument of the type defined in claim 5 and further characterized by the said air passage, compensator ducts, mouthpiece and bell members and the air valve members being in substantially the same vertical plane.

7. A musical instrument, comprising in combination a body member including top, bottom, front and rear end portions and having a circuitous air passage therein, the air passage terminating into a mouthpiece at the said rear end portion and into a bell at the said front end portion, the said air passage having a straight part extending longitudinally through the said top portion and having a wall thereat, the body member having a set of compensator ducts therein opening into the aforesaid wall, the said member also having laterally extending finger openings therein, and a set of air valve members mounted on the body member top portion and operating in the said straight part in a manner permitting the opening or the closing of the ducts at the said wall.

8. A musical instrument, comprising in combination, a body member including front and rear end portions having bell and mouthpiece portions respectively thereat and having an air passage running therethrough connecting the bell and mouthpiece portions, the said air passage 75

having a substantially straight part intermediate the said end portions and also having a wall portion therein, the body member also having a set of compensator air ducts therein entering into the aforesaid straight part at the side wall portion, and a set of air valve members mounted on the body member above the said straight part and operating therethrough in a manner permitting the opening or the closing of any of the said ducts thereat.

9. A musical instrument comprising in combination, a body member including front and rear end portions and having a circuitous air passage therein, the said passage running through the said portions and terminating into a mouthpiece and a bell at the said rear and front end portions respectively, the said passage having a straight part extending longitudinally through the said top portion and also having a bottom thereat, the body member having compensator ducts therein opening into the aforesaid part along the said bottom thereof, and air valve members mounted on the body member intermediate the front and rear end portions and above the straight part and operating therein in a manner permitting the opening or the closing of the ducts along the said bottom, the said circuitous air passage, compensator ducts and air valves being in the same vertical plane.

10. A musical instrument comprising in combination, a body member including front and rear end portions and having a circuitous air passage therein, the said passage running through the said portions and terminating into a mouthpiece and a bell at the said rear and front end portions respectively, the said passage having a straight part extending longitudinally through the said body member and also having a side wall thereat, channelled members mounted on the body member and forming with the said top portion compensator ducts opening into the said side wall, and air valve members mounted on the body member above the straight part and sliding therein in a manner permitting the opening or the closing of the said ducts at the said side wall.

11. A musical instrument of the type defined in claim No. 10 and further characterized by the said body member having finger openings below the said straight part and between the front and rear end portions.

12. A musical instrument, comprising in combination, a body member including top, bottom, front end, rear end and central portions and having an air passage therein terminating in a mouthpiece at the rear end portion and running downwardly therethrough to the bottom portion, thence forwardly therethrough to the central portion, thence rearwardly therethrough to the rear end portion, thence upwardly therethrough to the top portion, thence forwardly therethrough to the front end portion, thence downwardly therethrough to the bottom portion, thence rearwardly therethrough to the central portion, thence forwardly therethrough to the front end portion, thence upwardly therethrough to the top portion terminating in a bell, the part of the aforesaid circuitous air passage running through the top portion being substantially straight, the said body member having a plurality of compensator air ducts in the central portion thereof opening into the aforesaid substantially straight part; and a plurality of air valve members mounted on the body member top portion extending therethrough and operating in the said passage.

13. A musical instrument of the type defined in claim 12 and further characterized by the said air passage, compensator ducts and air valve members being in the same vertical plane.

14. A musical instrument, comprising in combination, a body member including top, bottom, front and rear end portions and having an air passage therein terminating in a mouthpiece at the rear end portion and running downwardly therethrough to the bottom portion, thence forwardly therethrough to the front end portion, thence upwardly therethrough to the top portion, thence rearwardly therethrough to the rear portion, thence forwardly through the top portion to the front portion terminating in a bell, the portion of the air passage running rearwardly through the top portion having a side wall thereat; channelled members mounted on the body member and forming with the said top portion compensator air ducts opening into the said air passage at the side wall thereof; and a plurality of air valve members mounted on the body member top portion extending therethrough and operating in the portion of the air passage running rearwardly through the top portion and in a manner permitting the compensator ducts to be opened or closed at the said side wall.

15. In a wind instrument of the type having a longitudinal air passage therethrough and compensator air duct termini opening therein, a valve, comprising in combination, co-acting leaf members having lever portions thereon hingedly mounted in the said instrument between the termini, the said leaf members closing the termini and opening the air passage when in a first position and opening the termini and closing the air passage when in a second position, a forked member operatively engageable with the said lever portions and extending across the air passage, a body portion receiving the forked member and mounted on the instrument substantially above the leaf members, and a tension means mounted in the body portion and engageable

with the forked member and normally permitting the leaf members to assume the said first position.

16. In a wind instrument of the type having a longitudinal air passage therethrough and compensator air duct termini opening therein, a valve, comprising in combination, co-acting leaf members hingedly mounted in the said instrument between the termini, the said leaf members closing the termini and opening the air passage when in a first position and opening the termini and closing the air passage when in a second position, a frame member operatively engageable with the leaf members and movable across the air passage, a body portion receiving the frame member and mounted on the instrument substantially above the leaf members, and a spring device mounted in the body portion and engageable with the frame member and normally permitting the leaf members to assume the said first position.

17. In a wind instrument of the type having a longitudinal air passage therethrough and compensator air duct termini opening in the side thereof, a valve, comprising in combination, a body member having side openings coinciding with the said duct termini openings and having end openings coinciding with the longitudinal air passage, a valve stem including a blade portion movably mounted in the body member, the said blade portion being movable across the air passage between the end openings and between the said side openings and in a manner permitting the closing of the duct and opening of the air passage when in a first position and the opening of the duct and closing of the air passage when in a second position, and a spring means mounted on the body portion and engageable with the valve stem normally permitting the blade portion to assume the said first position.
